MEANS FOR ERECTING PREFABRICATED HOUSES AND THE LIKE

Adele Burns, New York, N. Y.

Application March 12, 1936, Serial No. 68,420

12 Claims.

(Cl. 72—1)

This invention relates to new and useful improvements in the construction of a prefabricated house and the like.

The invention has for an object the construction of a prefabricated house which may be erected and taken down any number of times so that it is readily movable from one site to another, or from one city to another.

The invention contemplates constructing the house so that the elements thereof are held together in a manner to permit their erection and dismantling without any damage to the house. More specifically, it is contemplated to avoid the use of nails, screws, bolts, or the like.

A further object of the invention is the arrangement of vertical and horizontal spring clamps, adjustably mounted, so as to be capable of clamping the various elements constituting the house in fixed positions.

Still further the invention contemplates the provision of a foundation for the house (which cannot be moved) which is provided with receiving elements to coact with complementary receiving elements on portions of the house by which the house may be readily assembled thereon and dismantled when desired.

A further object of the invention is the construction of a house as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a small house constructed according to this invention.

Fig. 2 is a horizontal sectional view of the house showing the layout of the rooms.

Fig. 3 is a fragmentary enlarged elevational view looking in the direction of the line 3—3 of Fig. 1.

Fig. 4 is a fragmentary enlarged detailed view of the lower left hand corner of Fig. 2.

Fig. 5 is a fragmentary sectional view taken on the line 5—5 of Fig. 3.

Fig. 6 is a fragmentary sectional view taken on the line 6—6 of Fig. 3.

Fig. 7 is a perspective view of the lower portion of one of the columns used in the house.

Fig. 8 is a fragmentary enlarged sectional view taken on the line 8—8 of Fig. 1.

Fig. 9 is a fragmentary sectional view taken on the line 9—9 of Fig. 3.

Fig. 10 is a fragmentary enlarged detailed view of a portion of Fig. 1 showing in particular the arrangement of the exterior wall.

Fig. 11 is a fragmentary sectional view looking in the direction of the line 11—11 of Fig. 10.

Fig. 12 is a front elevational view of a portion of Fig. 11, but showing the spring clamp lifted into inoperative position.

Fig. 13 is a perspective view of Fig. 12.

Fig. 14 is a fragmentary enlarged detailed view of a portion of the spring clamp shown related to certain portions of the exterior wall.

Fig. 15 is a horizontal sectional view taken on the line 15—15 of Fig. 14.

Fig. 16 is a plan view of a corner column with the spring clamp and wall boards shown in Figs. 14 and 15 in position.

Fig. 17 is an elevational view of a portion of Fig. 1 showing the details at the upper right hand corner of one of the windows.

Fig. 18 is a fragmentary elevational view of the roof portion of the house.

Fig. 19 is a fragmentary perspective view of a portion of Fig. 18.

Fig. 20 is an elevational view of a portion of the inside wall of a house constructed according to this invention.

Fig. 21 is a sectional view taken on the line 21—21 of Fig. 20.

Fig. 22 is a vertical sectional view taken on the line 22—22 of Fig. 20.

Fig. 23 is a fragmentary perspective view of a portion of Fig. 20.

Fig. 24 is a perspective view showing a skeleton and some of the interior of the house.

The prefabricated house, according to this invention may be of any design or type, and of as many rooms as desired. It may be one story, or 40

more. The principle of construction is the same, the arrangement only would differ. The house shown in Figs. 1 and 2 is merely an example of how a house would be constructed according to this invention. The illustration shows a one story 45

house. It is composed of side walls 10, a roof 11, interior walls 12 which form the several rooms of the house, and other elements not listed in detail. The house is built on a foundation 13 (see Figs. 1 and 3).

The foundation, preferably, should be of cast concrete. It is cast to hold a plurality of socket members 15, 16, etc., which are adapted to receive various complementary portions from the house.

At the corners of the house there are vertical 55

- pillars or studs 17. Along the sides there are other studs 18, 19, etc. The lower ends of each of these studs are solid and are formed with small projections 20 (see Fig. 7). These projections are 5 adapted to engage into the socket members 15, 16, etc. The socket members 16 extend substantially along the entire width and length of the house so that the studs 18 may be engaged thereon at desired locations. For example, the dot and 10 dash lines 18' in Fig. 3, indicate two locations. The foundation 13 is also formed with inserts 20 adapted to receive and hold floor beams 21. The floor 22 of the house (see Fig. 2) is laid on the beams 21.
- 15 Each of the studs 17, 18, 19, etc., is adapted to support the siding or other prefabricated material forming the walls of the house. More particularly, the studs 18 are formed with grooves 24 upon the front and back faces thereof adapted to 20 receive hook elements 25 from wall panels or similar members 26. The stud 19 is substantially of T-shape and its outer face 19' is formed with grooves 24, as clearly shown in Fig. 4. Thus, the wall panels 26 are also supported thereby.
- 25 In addition to the grooves 24 certain of the studs are provided with spring clamps 27. These spring clamps, preferably are located within recesses formed in the corners of the studs. This may be clearly seen in Fig. 4, for example, in 30 which the stud 17 has recesses 17^a, 17^b, 17^c and 17^d into which the spring clamps 27 are set. Similarly, the studs 19 are also formed for receiving the spring clamps.
- 35 Each of the spring clamps comprises a rod 27^a secured at the top and bottom ends to the studs, preferably by brackets 30. Pivotedly mounted on the rods 27^a there are the body portions 27^b of the clamps. These body portions are suitably decorated with ornamental raised and depressed 40 portions, indicated in Figs. 14 and 15. Each of the body portions 27^b are formed with tail portions 27^c on the opposite side of the rod 27^a. These tail portions are engaged at spaced intervals by springs 31. These springs are cast at one of their ends 45 into the studs and extend through openings 32 in the tail portions 27^c. The springs 31 serve to urge the clamp into closed position.
- 50 These spring clamps are on all corner studs, on both exterior and interior sides, on the vertical sides of doors and windows and on baseboard and cornice.
- 55 The inside face of the extremities of the body portions 27^b of the spring clamps are provided with dowel pins 33 which are adapted to project into perforations 34 formed in the wall panels 26 or similar members. The uppermost panel (indicated by reference numeral 26') is held in position by a U-shaped clamp 35 which is engaged over the edge of the panel and the edge 60 of the spring clamp. With this arrangement it is possible to erect the walls of the house in position by starting at the bottom and working upwards. By clamping the uppermost board 26' of the wall the entire wall construction is held in 65 position. The walls or panels, in addition to being fastened by the pins 33 are also supported by the hook portions 25 thereof engaging into the grooves 24 as previously explained.
- 70 Now referring to Fig. 2 it will be readily apparent that the outer wall construction may be readily taken down since it is composed entirely of the removable parts as explained in the previous paragraphs. Also, the walls forming the various rooms are removable. The particular layout 75 shown on the drawings incorporates windows 36

into the wall structures. The frames of these windows are constructed similar to the studs. That is, they are formed with vertical grooves into which the spring clamps are mounted. This is clearly shown in Fig. 2.

5 In Figs. 1 and 2 the house is shown provided with a door 37, a small stoop 38 leading to the door, a chimney 39, a side entrance 40 for the house, etc. The bathroom of the house is indicated by reference numeral 41. All accessories as 10 well as the wall panels may be of any prefabricated type desired.

15 In Figs. 10, 12 and 13 other types of supports for the wall panels 26 are illustrated. These additional supports are in the form of hook-shaped 15 brackets 43 mounted upon the pillars or other support parts for the wall panels, and adapted to receive and hold stud elements 44 projecting from the ends of the shingles. With this construction the house will be sturdy and capable of 20 withstanding storms and other shocks.

25 The roof of the house is also constructed of prefabricated sections which are placed in position starting at the lowermost edge and working upwards. The top sections are locked into position with a spring clamp as are the wall panels and this clamp is locked with a key. More specifically, the house has a top member 46 from the sides of which the spring clamps 27 depend. These spring clamps are adapted to be locked 30 together by strips 47. Each of the strips 47 is hingedly mounted at one of their ends 47' to the spring clamp at one side, and extends across to the spring clamp at the other side. A key operated lock 48 is mounted on each of the strips 47 35 and is adapted to engage and lock the free end of the strip 47 to the spring clamp. The roof of the building is inclined, as clearly shown in Figs. 1 and 18 of the drawings. A flat roof could be locked in the same manner.

40 In Fig. 20 the interior form of the building is shown in which spring clamps 27^d are shown extended vertically at certain areas and horizontally at other areas. These spring clamps are arranged at the windows 36' and the door 37'. Panels 26^d are held by the spring clamps. The details of the spring clamps will not be given at this point as it would be a repetition of the description of the corresponding parts in the previous figures.

50 In Fig. 21 a sectional view is shown wherein it will be noted that the panels 26^d have pinned ends 26^{dd} to hold, reinforce and strengthen them. Similar reference numerals are used to indicate parts corresponding with similar parts in the previous form of the invention.

In Fig. 15 the dot and dash lines 27^b indicate a pivoted position of the spring clamp which permits the wall board 26 to be removed.

55 The house may be erected on any site by first building the foundation. The vertical studs are then mounted upon the foundation and the exterior and interior wall sections, including the windows, doors, etc., are mounted thereon. The house is finished by building upwards until the 60 roof is reached. At the uppermost portion of the roof the spring clamps are locked by lock and key. The house may be taken down by starting at the top, opening the locks, and taking the parts down. The house may be moved to a different 65 location. It is only necessary that a new foundation be built at the new site.

70 The house according to this invention is preferably erected in the following order:—

1. One-half of concrete foundation is formed.

2. Socket members 16 are inserted.
 3. Rest of concrete is set.
 4. Studs, floor beams, ceiling beams, rafters, ridge-pole clamps, etc., will be positioned.
 5. Flooring is laid.
 6. Outside walls laid horizontally and firmly in overlapping relation.
 7. Doors and windows set in at the same time, above the first layer of horizontal boards.
 10. Outside clamps are snapped in place.
 9. Inside base-boards, wall panels, cornices are set and clamped. The vertical clamps of doors and windows are snapped in place, then the base-board clamps, next the horizontal clamps across 15 the top of the walls and finally the corner clamps which are then fastened with U-shaped pieces.
 10. Ceilings are laid.
 11. Overlapping roof sections are erected toward the top.
 20. 12. Ridgepole clamps are snapped into place.
 13. Clamps at both ends of ridgepole are locked with key so that only authorized persons may open same for dismounting or repairing the building.
 25. While I have illustrated and described the preferred embodiment of my invention, it is to be understood that I do not limit myself to the precise construction herein disclosed and the right is reserved to all changes and modifications coming within the scope of the invention as defined in the appended claims.
 Having thus described my invention, what I claim as new and desire to secure by United States Letters Patent is:—
 35. 1. A means of constructing a prefabricated house and the like, comprising a foundation adapted to removably receive and hold vertical pillars, or studs, a plurality of vertical pillars or studs mounted on said foundation and formed 40 with wall receiving recesses, a plurality of hingedly mounted spring clamps on said pillars or studs and adapted to act as clamps for holding wall-forming elements, and a plurality of wall-forming elements rested upon said wall-receiving 45 recesses and held by said spring clamps.
 2. A means of constructing a prefabricated house and the like, comprising a foundation adapted to removably receive and hold vertical pillars, or studs, a plurality of vertical pillars or 50 studs mounted on said foundation and formed with wall receiving recesses, a plurality of hingedly mounted spring clamps on said pillars or studs and adapted to act as clamps for holding wall-forming elements, and a plurality of wall-forming elements rested upon said wall-receiving 55 recesses and held by said spring clamps, said foundation being of concrete and having imbedded therein socket members adapted to receive complementary parts from portions of the house.
 60. 3. A means of constructing a prefabricated house and the like, comprising a foundation adapted to removably receive and hold vertical pillars, or studs, a plurality of vertical pillars or studs mounted on said foundation and formed 65 with wall receiving recesses, a plurality of hingedly mounted spring clamps on said pillars or studs and adapted to act as clamps for holding wall-forming elements, and a plurality of wall-forming elements rested upon said wall-receiving 70 recesses and held by said spring clamps, said vertical pillars or studs, being formed with shoulders and hollow corners into which the hingedly mounted spring clamps are arranged.
 4. A means of constructing a prefabricated 75 house and the like, comprising a foundation

adapted to removably receive and hold vertical pillars or studs, a plurality of vertical pillars or studs mounted on said foundation and formed with wall-receiving recesses, a plurality of hingedly mounted spring clamps on said pillars or 5 studs and adapted to act as clamps for holding wall-forming elements, and a plurality of wall-forming elements rested upon said wall-receiving recesses and held by said spring clamps, said spring clamps comprising stationary rods supported upon the pillars or studs, body members pivotally mounted on said rods and having tail portions, and springs acting between the pillars and the tail portions for urging the spring clamps into the closed position. 10

5. A means of constructing a prefabricated house and the like, comprising a foundation adapted to removably receive and hold vertical pillars or studs, a plurality of vertical pillars or studs mounted on said foundation and formed 20 with wall receiving recesses, a plurality of hingedly mounted spring clamps on said pillars or studs and adapted to act as clamps for holding wall-forming elements, and a plurality of wall-forming elements rested upon said wall-receiving 25 recesses and held by said spring clamps, said wall-forming elements comprising wall boards. 15

6. A means of constructing a prefabricated house and the like, comprising a foundation adapted to removably receive and hold vertical 30 pillars or studs, a plurality of vertical pillars or studs mounted on said foundation and formed with wall receiving recesses, a plurality of hingedly mounted spring clamps on said pillars or studs and adapted to act as clamps for holding 35 wall-forming elements, and a plurality of wall-forming elements rested upon said wall-receiving recesses and held by said spring clamps, said wall-forming elements comprising wall boards, having projecting parts adapted to engage within said 40 recesses.

7. A means of constructing a prefabricated house and the like, comprising a foundation adapted to removably receive and hold vertical pillars or studs, a plurality of vertical pillars or 45 studs mounted on said foundation and formed with wall-receiving recesses, a plurality of hingedly mounted spring clamps on said pillars or studs and adapted to act as clamps for holding 50 wall-forming elements, and a plurality of wall-forming elements rested upon said wall-receiving recesses and held by said spring clamps, said wall-forming elements having brackets projected from the ends thereof, and hook members mounted upon said pillars or studs, and adapted 55 to receive and hold said brackets.

8. A means of constructing a prefabricated house and the like, comprising a foundation adapted to removably receive and hold vertical pillars or studs, a plurality of vertical pillars or 60 studs mounted on said foundation and formed with wall-receiving recesses, a plurality of hingedly mounted spring clamps on said pillars or studs and adapted to act as clamps for holding 65 wall-forming elements, and a plurality of wall-forming elements rested upon said wall-receiving recesses and held by said spring clamps, said wall-forming elements having brackets projected from the ends thereof, and hook members mounted upon said pillars or 70 studs, and adapted to receive and hold said brackets, said spring clamps having projecting dowel pins engageable into apertures in the wall-forming elements to assist in holding them in position. 75

9. A means of constructing a prefabricated house and the like, comprising a foundation adapted to removably receive and hold vertical pillars, or studs, a plurality of vertical pillars or studs mounted on said foundation and formed with wall receiving recesses, a plurality of hingedly mounted spring clamps on said pillars or studs and adapted to act as clamps for holding wall-forming elements, and a plurality of wall-forming elements rested upon said wall-receiving recesses and held by said spring clamps, said wall-forming elements being built from the bottom of the house upwards and overlapping each other, and means for locking the uppermost wall-forming elements in position.
10. A means of constructing a prefabricated house and the like, comprising a foundation adapted to removably receive and hold vertical pillars, or studs, a plurality of vertical pillars or studs mounted on said foundation and formed with wall receiving recesses, a plurality of hingedly mounted spring clamps on said pillars or studs and adapted to act as clamps for holding wall-forming elements, and a plurality of wall-forming elements rested upon said wall-receiving recesses and held by said spring clamps, said wall-forming elements being built from the bottom of the house upwards and overlapping each other, and means for locking the uppermost wall-forming elements in position, comprising hook elements engageable over the edges of the wall-boards and the edges of the spring clamps.

11. A means of constructing a prefabricated house and the like, comprising a foundation adapted to removably receive and hold vertical pillars or studs, a plurality of vertical pillars or studs mounted on said foundation and formed with wall receiving recesses, a plurality of hingedly mounted spring clamps on said pillars or studs and adapted to act as clamps for holding wall-forming elements, and a plurality of wall-forming elements rested upon said wall-receiving recesses and held by said spring clamps, said wall-forming elements being built from the bottom of the house upwards and overlapping each other, and means for locking the uppermost wall-forming elements in position, comprising strips pivotally mounted on certain of the spring clamps and carrying locks adapted to lock them to other of said spring clamps.
12. A means of constructing a prefabricated house and the like, comprising a foundation adapted to removably receive and hold vertical pillars or studs, a plurality of vertical pillars or studs mounted on said foundation and formed with wall-receiving recesses, a plurality of hingedly mounted spring clamps on said pillars or studs and adapted to act as clamps for holding wall-forming elements, and a plurality of wall-forming elements rested upon said wall-receiving recesses and held by said spring clamps, said wall forming elements comprising panels.

ADELE BURNS.
